CLAIM

We claim the ornamental design for a satellite equipment for robot, as shown and described.

DESCRIPTION

FIG. 1 is a front elevation view of a satellite equipment for robot showing our new design.

FIG. 2 is a rear elevation view thereof.

FIG. 3 is a top plan view thereof.

FIG. 4 is a bottom plan view thereof.

FIG. 5 is a right side elevation view thereof; and,

FIG. 6 is a left side elevation view thereof.

The curved line seen in FIGS. 3-6 represents a symbolic break in the length of the satellite equipment for robot cord and forms no part of the claimed design.
